[57] ABSTRACT

A bladed rotor having blading of flow-varying type, including, carried within its hub, a pump operable upon rotor rotation and valve means for controlling the flow of pressure fluid from the pump to a fluid-pressure-operable actuator for adjusting the blading. Conduit means, provided for conducting fluid to the pump inlet, are connectable to a source external of the rotor.

SHEET 3 OF 3

FIG. 3.

BLADED ROTORS

This invention relates to bladed rotors.

According to this invention a bladed rotor whose blading is of flow-varying type includes, carried within its hub, a pump operable upon rotor rotation, valve means for controlling the flow of pressure fluid from said pump to a fluid-pressure-operable actuator for adjusting the blading, and conduit means for conducting fluid to the inlet of the pump, said conduit means being connectible to a source external of the rotor.

The conduit means is connectible to the source by way of fluid transfer means whereby fluid can pass from non-rotatable structure to the rotor.

In practice, the conduit means may be connected to the lubrication system of an engine which is connected to drive the bladed rotor.

Further conduit means may be provided whereby fluid exhausting from said actuator can be directed through said fluid transfer means to said lubrication system.

The pump may be of the internally-meshing lobed type and the axis of its drive shaft may be coincident with the axis of rotation of the rotor.

The actuator may be of the vane-type and drive means from the actuator for adjusting the blading may include a balanced bevel gear train. In this case the valve means may be arranged coaxially with respect to the actuator and within a hub portion thereof.

The flow-varying blading is preferably of variable-pitch.

One embodiment of the invention will now be particularly described by way of example with reference to the accompanying diagrammatic drawings, of which,

FIG. 1 shows a gas turbine engine of the by-pass type having a bladed rotor, which forms a by-pass fan, shown partly in cross-section;

FIG. 2 is a cross-section of a gear casing forming part of the construction shown in FIG. 1;

FIG. 3 is a perspective view with parts cut away, of the rotary control valve, a vane actuator and the pitch-change pump for the rotor.

With reference to FIG. 1 of the drawings, a bladed rotor 11 includes seventeen blades, two of which are shown at 12. The blades are mounted in the hub 13 of the rotor so as to be variable in pitch about their longitudinal pitch-change axes 14. The bladed rotor 11 forms the by-pass fan of a gas turbine engine 15 of the by-pass type. This engine includes a duct 16 within which the rotor is rotatable. The inlet casing to the axial-flow compressor C of the engine is shown at 17 and a gear casing 18 forming part of the non-rotatable structure of the engine is provided ahead of the engine compressor. The combustion chamber section of the engine is shown at F and the turbine section at T. The compressor is connected to drive the rotor 11 through reduction gearing housed in the gear casing.

A pump 19 of the internally-meshing lobed type is mounted within the hub 13 for rotation therewith, the axis of its drive shaft 20 being coincident with the axis 21 of rotation of the rotor. This drive shaft is fixed to non-rotatable structure within the gear casing 18, so that the pump 19 is operable when the rotor 11 is being driven by the engine.

A conduit 22 is taken from a conventional lubrication system of the engine 15. The lubrication system includes an engine-driven pump 81 which draws liquid from a sump S and which delivers liquid under pressure to the anti-friction bearings of the rotating components of the engine. The conduit 22 connects to a fluid transfer means, shown diagrammatically in FIG. 1 at 23, designed to conduct hydraulic liquid from non-rotatable structure of the gear casing 18 to a conduit 24 in the rotatable structure of the hub 13. The conduit 24 connects with the inlet 25 of the pump 19. A conduit 26 is taken from the outlet 27 of the pump to a pitch control valve assembly, shown generally at 28, which is rotatable with the hub 13 and which is mounted therein with its axis coincident with the axis 21.

A drain conduit 29 is taken from the valve assembly 28 to the fluid transfer means 23 so that drain liquid can pass back

from the hub to a conduit 30 in the gear casing and back to the engine lubrication system.

The pitch control valve assembly 28 is positioned within the hub 31 of a fluid-pressure-operable actuator 32 of balanced-vane type. This actuator has its axis of rotation coincident with the axis 21 and includes a multiplicity of chambers 33 formed by a first multi-vaned actuator part 34 and by a second multi-vaned actuator part 35. Portions 36 and 37 of these parts carry respective bevel gear rings 38 and 39 which mesh with bevel gears 40, one fast with the root portion of each blade 12. As shown, the points of meshing of the bevel gear rings 38 and 39 with each bevel gear 40 are substantially diametrically opposed upon the latter.

An input member 41, mounted upon the non-rotatable structure of the gear casing 18, is provided to operate the valve assembly 28 through an epicyclic gear train, diagrammatically shown by the box 42. This gear train drives a gear 43 fast with the displaceable element 44 of the assembly 28, consequent movement of the element controlling the operation of the actuator 32 and thus blade pitch. Feedback means (not shown) is provided within the assembly by which the actuator cancels out the input signal to the displaceable element 44 as soon as the selected blade pitch adjustment has been reached.

Such a pitch control valve assembly and associated pitch-change actuator are disclosed in copending application Ser. No. 26,216, filed Apr. 7, 1970.

With reference now to both FIGS. 1 and 2 of the drawings, the fluid transfer means 23 shown diagrammatically in FIG. 1 is in FIG. 2 shown in detail within the gear casing 18. The drive shaft 20 for the pump 19 passes completely through the means 23 and at its right-hand end portion in the drawing carries a flange 45 which is bolted at 46 to a shoulder 47 formed integrally with the casing 48 of the means 23 and projecting into a stepped bore 49 thereof. The axis of the bore 49 is coincident with the axis 21, and the casing 48 is non-rotatable. A transfer sleeve 50 held against rotation by means of a peg 51 is provided in the bore 49. Annular recesses 52 and 53 are provided on the exterior surface of this sleeve, with three sealing rings 54, 55 and 56 provided in the positions shown. Ports 57 and 58 respectively place the recesses 52 and 53 in communication with annular recesses 59 and 60 on the inner surface of the sleeve. The sleeve is of steel and has white metal bushes 61, 62 and 63 dove-tailed into its inner surface, as shown, for rotational support of the rearward end portion of a tubular member 64 which is coaxial with, and which passes through, the main shaft 65 of the fan 12. The shaft 65 is partly supported by a ball bearing 66 and is driven from the compressor C through reduction gearing which includes a sun gear 67 mounted upon the output shaft 68 of the compressor, and planet gears 69 which are in mesh with the sun gear and which are also in mesh with an internally-toothed peripheral gear 70. The gear 70 is formed upon a cylindrical member 71, the forward end portion of which is splined at 72 to the rearward end portion of the shaft 65. There are four planet gears 69 and they are suitably mounted for rotation in the fixed casing 48.

Within the tubular member 64 is a first tube 73 coaxial with that member and screw-threadedly attached thereto. Within said first tube there is a second tube 74 coaxial with the member 64 and screw-threadedly attached thereto. Both the tubes 73 and 74 extend forwardly with the member 63 to the valve assembly 28, the tubular member and the two tubes being rotatable as one with the shaft 65. In this way two conduit means are provided, the first between the tube 73 and the tube 74, and the second between the tube 74 and the shaft 20. The first conduit means is the conduit 24 of FIG. 1 while the second is the conduit 29 of FIG. 1.

A second bearing, of roller type, shown at 80 in FIG. 2, supports the rearward extremity of the shaft 65.

Carbon seals 75 and 76 are positioned between fixed and rotating components of the transfer means as shown, spring-loaded means 77 and 78 being provided for axially loading the carbon rings in their sealing condition.

The annuli 52 and 53 respectively align with the inlet duct 22 and the return duct 30 shown in both FIGS. 1 and 2.

Although not shown in FIG. 1 there is a further conduit shown at 79, in FIG. 2, taken from the stepped bore 49 back to the sump S, this to collect liquid which seeps past the seals and white metal bushes in the transfer means.

In operation, when the engine 15 is operating to drive the by-pass fan 11, hydraulic liquid from the engine lubrication system is supplied at a base pressure of 40 p.s.i. through the conduit 22, the fluid transfer means 23 and the conduit 24 to the inlet 25 of the pump 19. The rotatable elements of the pump 19 receive this liquid and it is pumped at higher pressure through the outlet 27 into the conduit 26. This high pressure liquid is thus available at the pitch control valve assembly 28 for direction into the vane actuator to effect blade pitch-change at the demands of the input member 41.

Return liquid from the actuator 32, when pitch-change is actually occurring, is allowed to pass back to the engine lubrication system through the conduit 29, the transfer means 23 and the conduit 30.

During such operation the transfer means ensures that a minimum of liquid leakage occurs from the base supply conduit 22 to either the conduit 30 or the conduit 79, the sealing function being provided partly by the sealing rings 54 and 55 and partly by the white metal bushes 61 and 62. A slight seepage of liquid is permitted to occur between the white metal bushes and the rotating member 64 for lubrication purposes. This liquid passes, with any seepage past the seals 54 and 56, into the drain conduit 79.

The construction described ensures that relatively hot lubricating liquid delivered from the engine lubrication system is available at the inlet 25 of the pump 19, as compared with the cooler liquid which would have been available had the liquid been wholly contained within the fan hub. This relatively hot liquid gives much faster response at substantially all times during engine operation, such response being very desirable for the by-pass fans of engines of the by-pass type used in high speed aircraft where rapid pitch-change is necessary in all phases of fan operation.

By arranging that the inlet of the pump receives liquid at a substantial base pressure, there are likely to be no priming difficulties and the pump will operate with good efficiency.

Further, the fact that no reservoir is provided in the hub of the fan eliminates the need for reservoir-defining structure, and thus the size and weight of the fan hub are appreciably reduced.

Although in the embodiment above described the bladed rotor is the by-pass fan of a gas turbine engine of the by-pass type, in other embodiments the invention is with advantage applied to bladed rotors of the other kind, for example, propellers for aerial or non-aerial use.

Also in other embodiments, instead of the blading being of variable-pitch, it may be of variable-twist or variable-camber.

Again, the invention is not limited to blading of single tier form, as in other embodiments the blading may be of multiple tier type, one at least of the rows of which has flow-varying blading.

We claim:

1. In combination, a bladed rotor whose blading is of flow-varying type, an engine adapted to drive said rotor, a lubrication system forming part of said engine and including a sump and a low pressure pump, drivable by the engine, which is connected to draw liquid from the sump and to deliver that liquid at low pressure, said bladed rotor comprising a hub and, carried within the hub, a high pressure pump with means fast with non-rotatable engine structure whereby the pump is driven upon rotation of the rotor, a fluid-pressure-operable actuator for adjusting the blading, and valve means for controlling the flow of pressure fluid from said pump to the actuator, conduit means for conducting fluid from said low pressure pump to the inlet of the high pressure pump, said conduit means comprising one part provided in non-rotatable engine structure and another part in the form of a first tubular member carried by the rotor being rotatable therewith and extending into said drive shaft coaxially thereof, low pressure fluid transfer means associated with both said drive shaft and said rotor with which said one part and said first tubular member are connected thereby to afford substantially sealed fluid connection of those parts whereby low pressure liquid from said low pressure pump can pass to the inlet of said high pressure pump, and further conduit means, including a second tubular member coaxial with said first tubular member and also extending from said rotor into said drive shaft coaxially thereof, which are connected between said valve means and said sump by way of said low pressure fluid transfer means whereby liquid exhausting from the actuator can pass to said sump.

ing one part provided in non-rotatable engine structure and another part carried by the rotor and rotatable therewith, low pressure fluid transfer means associated with both said engine and said rotor and with which said one part and said other part of the conduit means are connected thereby to afford substantially sealed fluid connection of those parts whereby low pressure liquid from said low pressure pump can pass to the inlet of said high pressure pump, and further conduit means connected between said valve means and said sump by way of said low pressure fluid transfer means whereby liquid exhausting from the actuator can pass to said sump.

2. A bladed rotor as claimed in claim 1, wherein further conduit means are provided whereby fluid exhausting from said actuator can be directed through said fluid transfer means to said lubrication system.

3. A bladed rotor as claimed in claim 1, wherein said pump is of the internally-meshing lobed type, and the axis of its drive shaft is coincident with the axis of rotation of the rotor.

4. A bladed rotor as claimed in claim 1, wherein said actuator is of the vane-type.

5. A bladed rotor as claimed in claim 4, wherein drive means from the actuator for adjusting the blading includes a balanced bevel gear train.

6. A bladed rotor as claimed in claim 4, wherein the valve means is arranged coaxially with respect to the actuator and within a hub portion thereof.

7. A bladed rotor as claimed in claim 1, wherein said flow-varying blading is of variable-pitch.

8. A bladed rotor as claimed in claim 2, wherein said fluid transfer means comprises a sleeve fast with non-rotatable structure and supporting for rotation, with the drive shaft of said rotor, tubular members in part defining said conduit means and said further conduit means.

9. A bladed rotor as claimed in claim 8, wherein the parts of the conduit means and of the further conduit means defined by said tubular members are placed in communication with ducts, in said structure, which form the other parts of said conduit means, through respective annular recesses and porting formed in said sleeve.

10. In combination, a bladed rotor whose blading is of flow-varying type, an engine having a drive shaft upon which said rotor is mounted, a lubrication system forming part of said engine and including a sump and a low pressure pump, drivable by the engine, which is connected to draw liquid from the sump and to deliver that liquid at low pressure, said bladed rotor comprising a hub and, carried within the hub, a high pressure pump with means fast with non-rotatable engine structure whereby the pump is driven upon rotation of the rotor, a fluid-pressure-operable actuator for adjusting the blading, and valve means for controlling the flow of pressure fluid from said pump to the actuator, conduit means for conducting fluid from said low pressure pump to the inlet of the high pressure pump, said conduit means comprising one part provided in non-rotatable engine structure and another part in the form of a first tubular member carried by the rotor being rotatable therewith and extending into said drive shaft coaxially thereof, low pressure fluid transfer means associated with both said drive shaft and said rotor with which said one part and said first tubular member are connected thereby to afford substantially sealed fluid connection of those parts whereby low pressure liquid from said low pressure pump can pass to the inlet of said high pressure pump, and further conduit means, including a second tubular member coaxial with said first tubular member and also extending from said rotor into said drive shaft coaxially thereof, which are connected between said valve means and said sump by way of said low pressure fluid transfer means whereby liquid exhausting from the actuator can pass to said sump.
